UNITED STATES PATENT OFFICE.

ARTHUR CHARLES WATERS, OF NEWCASTLE, NEW SOUTH WALES, AUSTRALIA.

DUMPING BARGE OR LIGHTER.

1,306,322.

Specification of Letters Patent. Patented June 10, 1919.

Application filed October 15, 1918. Serial No. 258,230.

To all whom it may concern:

Be it known that I, ARTHUR CHARLES WATERS, of "Barrymore," Merewether Beach, Newcastle, in the State of New South Wales and Commonwealth of Australia, shipyard manager, have invented a new and useful Improved Dumping Barge or Lighter, of which the following is a specification.

10 This invention relates to lighters barges punts and the like used for transporting material such as rocks sand and mud which is to be dumped or discharged into water on which said barge floats as into the open sea.

15 And this invention has been specially devised in order to provide improved dumping barges such as tenders to dredgers which will transport loading and be operable at 20 will to capsize or turn completely over to dump or discharge said loading from one vessel or hull and present a reverse vessel or hull ready to receive further loading and so on continuously. And the improved

25 dumping barge or lighters dispense with expensive hopper doors below water and their accessories and further obviate the trouble expense and delays which occur with hopper barges or lighters by reason of hopper doors 30 allowing leakage of materials specially during towage by not closely fitting owing to materials getting jammed and the doors frequently becoming strained (necessitating docking or slipping of the barges or lighters 35 for repairs). And moreover the improved barges enable a loading even of soft and perhaps clingy material to be expeditiously discharged even after said loading has been

40 therein for some time and enable rock stone and like loads to be discharged more readily and satisfactorily and efficiently than from hopper barges and further enable the hulls or vessels of the improved barges to be repaired in case of damage without the necessity 45 of docking or slipping them and furthermore dispenses wholly or partly with a crew or attendants.

This improved dumping barge or lighter consists of two pontoons connected and tied 50 together longitudinally and ended so as to provide two (preferably water-tight) vessels or hulls back to back each of which vessels or hulls is preferably of equal capacity and has a controllable scupper or drain 55 valve and may have controllable flooding valve.

This improved barge has preferably bow or nosed ends and has preferably cross or strong beams athwart ship or may be bulk heads or like ties. And one or both pontoons may be divided into compartments each having a controllable flooding valve or valves and escapes or air pipe or pipes with an overwater discharge end. 60

In order that the invention may readily 65 be carried into practice the same will now be described with reference to the drawings accompanying this complete specification in which diagrammatically Figure 1 is a plan Fig. 2 a side elevation and Fig. 3 a cross 70 sectional elevation respectively of a preferred construction of this improved dumping barge or lighter and Figs. 4 and 5 are similar cross sections illustrating modified constructions of the pontoons. 75

The pontoons 10 preferably of square shape in cross section are positioned diamondwise and distanced sufficiently to render the barge stable with the desired load and joined say horizontally at their nearest 80 angles by a flat or bottom 11 and to each vertical angle is preferably affixed a bulkhead or coaming 12 which is continued across as part of the ends of two back to back or oppositely disposed hulls or vessels 85 8 and 9 of approximately equal capacity. The bow end 13 is set angularly from the center line to diminish resistance by the water while the stern end 14 is vertical though both may have the same set as desired. Within the hulls or vessels are strong beams 15 or floors bulkheads or the like. If desired wooden fenders 7 are affixed at each side of the barge to protect it against 90 contacting objects and these fenders (when 95 say the water line after overturn of the barge is at about the angle of the pontoons) increase the local water plane and thus increase the stability of the barge immediately after it has overturned and additionally hold it while the flooded compartment 9 which is then uppermost drains and the barge regains its normal stability. 100

In the construction shown in Fig. 3 one of the pontoons 10 is divided by a diagonal 105 flat 16 into two watertight compartments 17 and 18. Each compartment has a valve or gate 19 and a drain and air pipe or pipes 20 extending above the load water line of the barge. 110

The extra weight of the division in one pontoon is counter balanced by construc-

- tional details in the other pontoon or by ballasting. Each vessel is provided with drains or valves 26 or both through which the water contained in the upturned vessel will drain off. Any suitable construction of valves or gates operatable by hand or operatable by a rod or connection cord from an attending tug or other vessel or operatable by other suitable means may be utilized.
10. Although the preferred construction of division of the pontoon into compartments 17 and 18 as shown in Fig. 3 these compartments may be made by cross flat 23 in dotted lines or by disturbed diagonal 24 as shown in Fig. 4 and in this construction an additional or auxiliary compartment or tank 22 is preferably provided between the pontoons formed by joining flats or decks 21 and such tank 22 has means for flooding same either direct or from a compartment of the pontoon and also has air valves and discharge valves.

In the modified construction as shown in Fig. 5 the pontoons 10 are connected by two flats or decks 25 forming an extension of the compartments of the divided pontoon across the center of the barge thus allowing the water in said compartments when same has been turned over to spread toward the 30 middle line of the barge and assist the barge to right herself.

In use the barge receives loading upon or in the upper hull or vessel 8 and is transported say by towage to the dumping locality. The lower compartment 18 of one pontoon 10 is now flooded by opening valve 19 preferably by means of a cord or the like from the tug and the barge will list and completely overturn when sufficient 40 water has entered through said valve 19 taking the place of the air passing out through drain pipes 20. The flooded compartment 18 then becomes uppermost and the water therein escapes through the drain 45 pipes 20 the water contained in the now upper vessel 9 discharges itself through the valves 26 and the barge regains an even keel ready for another loading in the said upper hull or vessel 9 which loading may be dumped by operating flood valve 19 with 50 similar effect to that just described.

In a further though more costly construction for large barges with light draft each pontoon is divided by flats forming water-tight compartments provided with flooding valves and drain and air valves. These compartments are so placed in the pontoons that the flooding thereof in a laden barge will not materially affect the position

of the center of gravity of the laden barge 60 other than if anything raising it causing it vertical sinkage and a consequently decreased water plane and lowering the position of the transverse meta-center until it is unstable causing it to list and overturn. 65

The barge having light draft will allow of these flooded compartments draining themselves after the barge has overturned.

Instead of being solid the ends of the barge may have for each vessel or hull 70 gates or other openings or a sliding door with float so that when the barge turns over the openings or doors will allow the submerged portions of the pontoons to pass free through the water when the barge is 75 being towed without presenting a broad end against the water.

If desired an ordinary rudder and operating mechanism may be provided.

What I claim is:—

1. A dumping barge or lighter comprising two pontoons connected together side by side and having opposing walls inclined with respect to each other to form two hulls back to back, and means for admitting water 85 to at least one of the pontoons to render the barge unstable.

2. A dumping barge or lighter comprising two pontoons of rectangular cross-section connected together side by side with their longitudinal angles opposite each other to form two hulls back to back, and means for admitting water to one at least of said pontoons to render the barge unstable. 95

3. An improved dumping barge or lighter comprising two pontoons united longitudinally by a flat or deck so as to form two hulls back to back and controllable valves for admitting water into such pontoons for 100 rendering the barge unstable substantially as described.

4. An improved dumping barge or lighter constituted of pontoons distanced and joined by a flat or deck, one at least of said 105 pontoons having water-tight compartments contained in said pontoons, and devices to enable the flooding and draining of said compartments, substantially as herein described and explained.

In testimony whereof I have signed my name to this specification in the presence of two subscribing witnesses:

ARTHUR CHARLES WATERS.
